UNITED STATES PATENT OFFICE.

JOHANN JACOB KEYSER, OF AARAU, SWITZERLAND.

ACTUATING MECHANISM FOR SPINNING AND TWISTING MACHINES.

Application filed April 7, 1927, Serial No. 181,777, and in Switzerland April 16, 1926.

This invention is concerned with an improved actuating mechanism for spinning, twisting and the like machines, particularly of so-called double-sided machines having two distanced pinion-driven main shafts for the actuation of the spindles and of the feeding and stretching mechanisms. As far as I know the actuation of this type of spinning and twisting machinery has so far hitherto been effected individually for each machine side by independent mechanism or by a mechanism common to both sides and so constructed and arranged that either one side only is in operation and the other one at rest or that both sides are run simultaneously and at one variable speed, so that an independent speed variation on both sides of the machine is not possible.

According to this present invention the main driving pinions arranged on both machine sides for the actuation of the respective spindles and feeding and stretching appliances are so arranged as to cooperate, respectively, with a special intermediate pinion of such a size and location that both intermediate pinions may mesh with each other and with their respective main pinions, when being in their one operative position, in order that both sides may be driven by one motor and at an unvariable, preferably the same, speed, means being provided for also so locating at least the one of the intermediate pinions that the same are no longer in mutual intermeshment but are merely meshing with their respective main pinions so that the machine sides can be driven in mutual independence by separate motors and at any desired variation of their actual and relative speeds. It thus becomes possible to either drive both sides of the machine and the spindles and stretching and feeding mechanisms pertaining thereto at the same speed or unvariable speed ratio and by means of one motor or to drive them at the same or at different speeds by means of two motors, whereby the efficiency of this type of spinning and twisting machines is considerably increased at the exclusion of an increase of the number of operating parts.

In the drawing illustrating a preferred embodiment of my invention

Fig. 1 is a front view of the main bearing shield of a spinning or twisting machine, the shield cover being omitted for the sake of clear illustration,

Figs. 2 and 3 are side and plane views respectively of Fig. 1,

Fig. 4 is a fractional front view corresponding to Fig. 1, after the intermediate pinions having been dislocated for independent drive of both machine sides.

Fig. 5 is a plane view of the pinion setting illustrated in Fig. 4.

The machine illustrated in the drawing and embodying my invention belongs to the so-called double-sided type of spinning and twisting machinery at which the spindles 1 are driven by worm gears 2 and a common actuating shaft 3. Machines of this type require, that the actuating shaft be driven in a definite direction with relation to the spindles 1, in order that the spindles may be kept in their proper positions by the pressure of the worm gears. The shaft 3 is carried by the spindle beam 4, its end projecting into and carrying within the main bearing shaft 5 an actuating pinion 6. The pinions 6 are meshing, respectively, with a main actuating pinion 7 carried by a main actuating shaft 8 which is supported in and by shield 5. Between the main pinions 7 I so arrange two pinions 9 on shafts 10 that the same mesh with each other and with the main pinions 7, as illustrated in Figs. 1-3. The shafts 10 are at their outwardly projecting ends provided with coupling means 11 for the attachment to the shaft of a motor, by which the shafts 10 and their pinions 9 may be rotated. When the pinions 9 are in intermeshment as shown in Figs. 1-3 one motor 12 only is necessary for simultaneously actuating both sides of the machine which, as the pinions 9 and 7 of both machine sides are provided with the same number of teeth respectively, will thus run at the same number of revolutions.

It is frequently required however in the actual use of such machines, that both sides be independently driven in order that yarn of different kind may be produced on and by both machine sides. For this purpose my improved machine requires no additional parts or mechanisms, it being only necessary to withdraw the pinions 9 with their shafts 10 and to mount them into bearings 13 arranged on the main bearing shield 5 so that the pinions 9 are only meshing with their respective main pinions 7, as illustrated in Figs. 4 and 5. Since either shaft 10 is provided with the coupling 11 either side can

at this position of the pinions 9 be independently driven by a separate motor 13^a, which will now act on one main pinion 7 only. Accordingly each side of the machine can be 5 run at a different number of revolutions in order to manufacture yarn of different kind.

Preferably the pinions 6, 7 and 9 are located within the main bearing shield 5 in separate casings 14 adapted to be closed by 10 lids 15. In Fig. 1 the left hand lid or cover 15 is dismounted in order that the inside of the gear casing may be revealed. The main shield 5 can be completely closed by an outer 15 protecting plate or lid 16 as shown in Fig. 2.

16. What I claim as my invention is:—

1. An actuating mechanism for spinning and twisting machines comprising two driving pinion gears and intermediate pinions between the same adapted to have two different relations to the driving gears and to each other in the one of which they are meshing with pinions of the driving gears and with each other so as to establish synchronism between both driving gears and to 20 permit actuation thereof by means of one motor and in the other of which they are only meshing with pinions of the driving gears so as to permit independent actuation 25 thereof by two separate motors.

30. 2. An actuating mechanism for spinning and twisting machines comprising two distanced driving gears each having a main driving pinion, intermediate pinions meshing with the main driving pinions respectively and two bearings for at least one of the said intermediate pinions so arranged that, when the said intermediate pinion is mounted in the one bearing it meshes with its main pinion and with the other intermediate pinion so as to establish synchronism between both driving gears and to 35 permit actuation thereof by one motor, whereas, when the said intermediate pinion is mounted in the other bearing it is out of mesh with the other intermediate pinion and only in mesh with its coordinated main pinion so as to permit independent actuation of both driving gears by separate motors.

40. 3. An actuating mechanism for spinning and twisting machines comprising two distanced driving gears each having a main driving pinion and two intermediate pinions each adapted to be mounted in two different bearings, the said bearings and intermediate pinions being so related, that when the intermediate pinions are mounted in their one

bearing they are meshing with their coordinated main pinions and meshing with each other so as to establish a positive train of gears between the two driving gears and to 45 permit synchronous actuation of the same by means of one motor, whereas, when the said intermediate pinions are mounted in the other bearings they are out of mutual intermeshment and only meshing with their 50 coordinated main pinions so as to permit an independent actuation of both driving gears by separate motors.

4. An actuating mechanism for spinning and twisting machines comprising two distanced driving gears each having a main driving pinion, intermediate pinions meshing with the main driving pinions respectively, two bearings for at least one of the said intermediate pinions so arranged that, when the said intermediate pinion is mounted in the one bearing it meshes with its main pinion and with the other intermediate pinion so as to establish synchronism between both driving gears and to 55 permit actuation thereof by one motor, whereas, when the said intermediate pinion is mounted in the other bearing it is out of mesh with the other intermediate pinion and only in mesh with its coordinated main pinion so as to permit independent actuation of both 60 driving gears by separate motors, and motor-coupling means for each driving gear.

5. An actuating mechanism for spinning and twisting machines comprising two distanced driving gears each having a main driving pinion and two intermediate pinions each adapted to be mounted in two different bearings, the said bearings and intermediate pinions being so related, that when 65 the intermediate pinions are mounted in their one bearing they are meshing with their coordinated main pinions and meshing with each other so as to establish a positive train of gears between the two driving 70 gears and to permit synchronous actuation of the same by means of one motor, whereas, when the said intermediate pinions are mounted in the other bearings they are out of mutual intermeshment and only meshing with their coordinated main pinions so as to permit an independent actuation of both 75 driving gears by separate motors, and motor-coupling means on either intermediate pinion.

In testimony whereof I affix my signature.

JOHANN JACOB KEYSER.
